US0D1055387S

(12) **United States Design Patent** (10) **Patent No.:** **US D1,055,387 S**
(45) **Date of Patent:** **** Dec. 24, 2024**

(54) **HAIR CLIPPER**

- (71) Applicant: **GAMMA PIU' S.R.L.**, Cazzago San Martino (IT)
- (72) Inventor: **Paolo Sterzi**, Cazzago San Martino (IT)
- (73) Assignee: **GAMMA PIU' S.R.L.**, Cazzago San Martino (IT)

(**) Term: **15 Years**

(21) Appl. No.: **29/914,896**

(22) Filed: **Oct. 23, 2023**

Related U.S. Application Data

- (62) Division of application No. 35/515,703, filed on Nov. 16, 2022 (U.S. filing date under 35 U.S.C. 384), and having an international filing date of Nov. 16, 2022, now Pat. No. Des. 1,016,395.

(57) **CLAIM**

The ornamental design for a hair clipper as shown and described.

DESCRIPTION

FIG. 1 is a perspective view of the design;

FIG. 2 is a right view thereof;

FIG. 3 is a left view thereof;

FIG. 4 is a front view thereof;

FIG. 5 is a rear view thereof;

FIG. 6 is a top view thereof; and,

FIG. 7 is a bottom view thereof.

The broken lines showing portions of the hair clipper form no part of the claimed design.

1 Claim, 6 Drawing Sheets
